US00D974959S

(12) **United States Design Patent** (10) **Patent No.:** **US D974,959 S**
(45) **Date of Patent:** **** Jan. 10, 2023**

(54) **AERIAL VEHICLE**

(71) Applicant: **SZ DJI Technology Co., Ltd.**,
Shenzhen (CN)

(72) Inventors: **Chenjie Wang**, Shenzhen (CN);
Yanyao He, Shenzhen (CN); **Xingchi Cheng**, Shenzhen (CN); **Yadong Wang**, Shenzhen (CN); **Yingtian Tan**, Shenzhen (CN); **Yiwei Chen**, Shenzhen (CN)

(73) Assignee: **SZ DJI Technology Co., Ltd.**,
Shenzhen (CN)

(**) Term: **15 Years**

(21) Appl. No.: **29/766,716**

(22) Filed: **Jan. 18, 2021**

(51) LOC (14) Cl. **12-06**

(52) U.S. Cl.

USPC **D12/16.1**

(58) **Field of Classification Search**

USPC D12/16.1, 223, 1-4, 319-346; D21/301, D21/436, 441-444, 447-455

CPC B64C 39/024; B64C 2201/108; B64C 2201/141; B64C 2201/024

See application file for complete search history.

(57) **CLAIM**

The ornamental design for an aerial vehicle, as shown and described.

DESCRIPTION

FIG. 1 is a top front perspective view of an aerial vehicle showing the claimed design;

FIG. 2 is a top rear perspective view thereof;

FIG. 3 is a bottom rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

1 Claim, 7 Drawing Sheets
